UNITED STATES PATENT OFFICE.

GEORGE E. KOEHLER AND JOHN SEYBOLD, OF CHICAGO, ILLINOIS.

BOOKBINDING.

1,179,935.

Specification of Letters Patent. Patented Apr. 18, 1916.

Application filed August 28, 1915. Serial No. 47,784.

To all whom it may concern:

Be it known that we, GEORGE E. KOEHLER and JOHN SEYBOLD, citizens of the United States, residing at Chicago, in the county of Cook and State of Illinois, have invented 5 certain new and useful Improvements in Bookbinding, of which the following is a specification.

Our invention relates to the art of bookbinding, and more particularly to the operation 10 of sewing together sections or signatures of a book.

One of the principal objects of the invention is to provide a satisfactory method of 15 sewing the sections directly one to another so as to do away with the use of cords or bands.

A further object is to accomplish the sewing operation in such manner that the back 20 of the book will be smooth; this object having reference more especially to a tight back binding in which the leather or cloth of the binding is glued or pasted directly to the back of the sewed sections. It is an objection 25 to certain of the prior methods aiming at the elimination of bands, that the edges of the sewed sections are covered with numerous threads which, extending back and forth in all directions and one over the other, 30 cannot be smoothed out so that they do not show through the binding. In a book sewed according to the method to be hereinafter described and claimed, the thread of the stitching is largely between the leaves of the 35 book. There are but a few short threads on the back and these do not overlap each other but extend transversely of the book so that when the back of the book is filled with 40 glue and shaped for the binding it will present a perfectly smooth surface for the leather or cloth of the binding.

A further object of the invention is to provide a stitching for the sections or signatures obviating the necessity of bands or 45 cords, which will be very strong and durable and at the same time flexible so that the book may be opened out flat easily and without danger of tearing out the stitches.

The invention is illustrated, in a preferred embodiment, in the accompanying drawings wherein—

Figure 1 is a view, in elevation, of a bench suitable for carrying on the sewing operation showing a number of the sections or 55 signatures of a book sewed together and another section in the process of being sewed

thereto. Fig. 2 is a plan view of the first section of the book. Fig. 3 is a detail view, in perspective, showing the character of the stitching on this section. Fig. 4 is a perspective view showing the second section of the book sewed to the first section. Fig. 5 is a detail perspective view, with the sections shown in outline only, illustrating the first stitch which joins the second section 60 to the first section. Fig. 6 is a similar view illustrating one of the other stitches between the first and second sections. Fig. 7 is a fragmentary perspective of the book completely sewed. Fig. 8 is a section on 65 line 8—8 of Fig. 7. Fig. 9 is a perspective view, with the book shown in outline, illustrating the manner in which the third section, and each successive section except the last one, is sewed to the preceding sections. 70 Like characters of reference designate like parts in the several figures of the drawings.

It will be understood that it has been necessary in the drawings to exaggerate the dimensions in certain respects for the purpose of more clearly illustrating the various parts of the book particularly described in the specification. The sections of the book have been shown as thicker than they will ordinarily be, the thread heavier and the 80 perforations in the sections larger. In Fig. 7 the complete book is shown as consisting only of five sections. Most books will consist of a considerably larger number of sections. 90

In carrying out the sewing operation of our invention the sections A, B, C, D and E are preferably formed with a series of perforations a, b, c, d, e, f, g, h, i along the back edge of the sections. This operation 95 can be performed with any suitable punching machine. The number will depend upon the size of the book.

While it is perhaps not essential we prefer before sewing the second section B to 100 the first section A to stitch section A through the aforesaid perforations with a stitching of the same sort employed for sewing the sections one to the other. This operation is shown in Figs. 2 and 3. The thread 105 X is first passed through opening a in section A, brought around the back edge of the section and tied at 10. It is then carried along the top of the section substantially parallel to the back edge thereof, as 110 indicated at 11, and passed down through opening b, as indicated at 12, around the

back of the book, as indicated at 13, then around the portion of the thread 11 just before it enters opening *b*—preferably knotted thereto, as indicated at 14,—and then on to the next perforation *c* where the same stitch is repeated. This operation is continued along the entire length of the section, the stitching consisting, it will be seen, of a series of stitches or loops, which extend through the section and around the back edge thereof in a plane substantially at right angles to the length of the book, joined by connecting stitches which will lie within the book and with which said transverse stitches have a looped or knotted engagement.

Figs. 4, 5 and 6 illustrate the manner in which the second section B is sewed to the first section. After the last stitch has been made through the perforation *i* in the upper corner of section A the thread is passed around the back of section B, as indicated at 15, down through the perforation *i* of section B and the perforation *i* of section A, as shown at 16, around the back of both sections, as shown at 17, knotted as shown at 18 to the portion of the thread just before it enters the perforation *i* in section B, and then along the upper surface of section B parallel with the back edge thereof, as indicated at 19, to the perforation *g* where the same stitch is repeated (Fig. 6), the thread being knotted again at the perforation as shown at 20. The thread, it will be seen, passes by the opening *h*. Section B is sewed to section A in this manner through every other perforation until the lower corner of the sections has been reached.

The third section (and the same is true of each succeeding section except the last one) is sewed to the preceding sections in the manner shown in the detail in Fig. 9. The last stitch uniting section B with section A is at the lower corner of the book, that is, through perforation *a*. After the thread has been knotted or looped around itself adjacent the perforation *a* in section B, as indicated at 21, it passes around the back edge of section C, as at 22, straight down through the perforation *a* in sections C and B, as at 23, and then, preferably, out through the back or folded edge of section A, as indicated at 24. It then passes around the upper portion of the back edge of section A and around the back edges of sections B and C and after being knotted or looped around itself, as shown at 25, is carried to the perforation *c* and so on through alternate perforations, until the upper corner of the book is reached.

While we prefer that the stitches should pass through the perforations of two sections and then out through the back of the next section below, as described, it will be possible to obtain certain of the advantages of the invention by bringing the needle out

between sections B and A instead of sewing through the back of section A. The fact that the stitching is through alternate perforations makes it possible to spread sections A and B to allow the needle to emerge from between them. It will also be possible to have the stitches pass completely through only one section, that is, through the perforation in section C, and then out through the back of the section below. However, this would not give as strong and durable a stitching as the preferred method first described.

It will be observed that while the stitching of each section to the next through the intermediate perforations *b* to *h* inclusive, is only through every other perforation (this method being desirable both as a matter of convenience in sewing and also to give the book a maximum flexibility) each section is sewed to the preceding sections through the end perforations *a*, *i*. The purpose of this is to give the sewing strength at the upper and lower corners of the book where strength is required. The stitching through the end perforations takes the place and performs the function of the ordinary kettle stitching.

The preferred method of sewing the last section is shown in Figs. 7 and 8. If the book consists of five sections, as shown, the thread will be at the lower corner of the book after the fourth section, D, has been sewed on. The thread emerging from the back of section B, as indicated at 26, passes around the back of sections C and D, as at 27, is looped or knotted to itself in the manner above described, passes around the back of section E, as at 28, down through perforation *a* out through the back of section C, 105 around sections D and E, as at 29, and after being looped or knotted around itself, as at 30, passes along the top of the section at 31, and enters perforations *b* at 32. A stitch is made through perforation *b*, as indicated at 33, and then through perforations *d*, *f*, *h* and *i*, as indicated at 34, 35, 36 and 37, respectively. A return is then made to the lower corner of the book through the alternate perforations, forming stitch 38 through 115 *g*, 39 through *c*, and 40 through *c*. The end of the thread is then knotted, as shown at 41, to the portion of the thread forming stitch 28. The stitches in this last series, 38, 39 and 40, pass through section E and 120 through the back of the section D, instead of passing completely through two sections and out through the back of the next preceding section as heretofore described. This is merely for convenience in sewing. It 125 would be difficult to sew section E completely through sections D and C at the points at which sections D and C are sewed to each other.

The necessity of illustrating the opera- 130

tions above described somewhat diagrammatically and in a manner which exaggerates certain dimensions will be recognized. For example, the loops or knots of the thread around itself after each stitch around the backs of the sections should ordinarily be closer to the perforations in the sections than they are shown in the drawings. The knots or loops themselves are drawn tighter. But to show the stitching on a scale and exactly as it appears in a book and at the same time adequately illustrate the manner in which the sewing operation is accomplished is not feasible.

In Figs. 7 and 8 the book is shown as provided with the usual upper and lower hinge strips *f* and *g* of muslin or other suitable tough fabric. These strips are sewed in with the upper and lower sections *E*, *A*, respectively.

It will be seen that our improved stitching eliminates the necessity of cords or bands on the back of the book and at the same time affords a means of securing the sections together which is very strong and durable. A book thus sewed is as flexible as can be desired. Each section is secured to the adjacent section or sections by stitches which are, in effect, closed loops or rings. These stitches are not put under any considerable stress when the book is opened so that it opens easily and there is no danger that the stitches will tear out of the paper. A knot is preferably formed as each loop is made so that these loops are, in effect, separate units or hinge rings, as they might be termed, the breaking of one of which does not affect the others. This form of stitching has the advantage that it can be used when the sections consist of single sheets as well as when they are made up of folios one within another. Furthermore, there is very little thread on the back of the book. When the book is formed the few transversely extending threads may be readily flattened down so that these stitches will not show through or produce unevenness in the back of the binding. Most of the thread employed in the stitching lies between the sections instead of on the back.

We claim:

1. A book comprising a plurality of sections, a stitching comprising closed loops which extend through the sections and around the back edges thereof, and connecting stitches which lie between the sections with which the aforementioned loops have knotted engagement, respectively.

2. A book comprising a plurality of sections, a stitching comprising closed loops which extend through the sections and around the back edges thereof at right angles to the length of the book, and connecting stitches which lie between said sec-

tions and parallel to the back edges thereof with which the aforementioned loops have knotted engagement respectively.

3. A book comprising a plurality of sections, a continuous stitching in which the thread passes through a plurality of the leaves of the book, then around the back edge of the same, then around the portion of the thread which passes through the leaves as aforesaid, then along the back edge of one of the leaves within the book and through said leaves again, and so on in the same manner.

4. A book comprising a plurality of sections which are sewed each to the preceding section at points between the points at which said preceding section is sewed to the section preceding it by means of closed loops extending around the back edges of said sections and connecting stitches lying between contiguous leaves of the adjacent sections respectively.

5. A book comprising a plurality of sections which are sewed each to the preceding section by stitches passing in each case completely through two sections and around the back edges thereof at points between the points at which said preceding section is sewed to the section preceding it.

6. A book comprising a plurality of sections which are sewed each to the preceding section at points between the points at which said preceding section is sewed to the section preceding it by means of a continuous thread engaged with itself at intervals to form loops extending completely through and around the back edges of a plurality of sections.

7. A book comprising a plurality of sections which are sewed each to the preceding section by stitches passing through two sections and out through the back of an adjacent section at points between the points at which said preceding section is sewed to the section preceding it.

8. A book comprising a plurality of sections which are sewed each to the preceding section by stitches passing through two sections and around the back edges thereof at points between the points at which said preceding section is sewed to the section preceding it, said stitches being connected by connecting stitches which lie between the sections along and adjacent to the back edges thereof.

9. A book comprising a plurality of sections which are sewed each to the preceding section by stitches which pass through the back of another section at points between the points at which said preceding section is sewed to the section preceding it.

10. A book comprising a plurality of sections sewed each to the preceding section by a series of stitches in which the thread passes

through a plurality of sections around the back edges thereof and around itself adjacent the place where it enters said sections.

11. A book comprising a plurality of sections sewed each to the preceding section by a series of stitches in which the thread passes through a plurality of sections around the back edges thereof and around itself adjacent the place where it enters said sections, 10 and then along the back edge of one of the sections within the book to the next stitch.

12. A book comprising a plurality of sections sewed each to the preceding section by a series of stitches in which the thread passes 15 through a section and out through the back of another section and around the back edges of said sections.

13. A book comprising a plurality of sections sewed each to the preceding section 20 by a series of stitches in which the thread passes through a section and out through the back of another section and around the back edges of said sections, and around the edge of one of the sections within the book to 25 the next stitch.

14. A book comprising a plurality of sections which are sewed each to the preceding section by a series of stitches in which the thread passes through a plurality of sections 30 out through the back of an adjacent section, around the back edges of said sections and along the edge of one of the sections within the book to the next stitch.

15. A book comprising a plurality of sections which are sewed each to the preceding section by a series of stitches in which the thread passes through a plurality of sections out through the back of the adjacent section, around the back edges of said sections, around itself at the point where the thread enters the sections as aforesaid, and along the edge of one of the sections within the book to the next stitch.

16. A book comprising a plurality of sections which are sewed each to the preceding section by a series of stitches in which the thread passes through a plurality of sections out through the back of the adjacent section, around the back edges of said sections, around itself at the point where the thread enters the sections as aforesaid, and along the edge of one of the sections within

the book to the next stitch; each section being thus sewed to the preceding section at points between the points at which said preceding section is sewed to the section preceding it.

17. A book comprising a plurality of sections which are sewed together by stitches forming closed loops or rings passing 60 through the sections and around the back edges of the same, each section being sewed to the preceding section at points between the points at which said preceding section is sewed to the section preceding it. 65

18. A book comprising a plurality of sections which are sewed together by stitches forming closed loops or rings passing through a plurality of sections out through the back of another section and around the back edges of said sections. 70

19. A book comprising a plurality of sections which are sewed together by stitches forming closed loops or rings passing through a section out through the back of 75 another section and around the back edges of said sections.

20. A book comprising a plurality of sections which are sewed together by stitches forming closed loops or rings passing 80 through the sections and around the back edges of the same, the stitches being joined by connecting stitches lying between the sections along the back edges thereof.

21. A book comprising a plurality of sections which are sewed together by stitches forming closed loops or rings passing through a plurality of said sections out through the back of an adjacent section and around the back edges of said sections; each 90 section being sewed in this manner to the preceding section at points between the points at which said preceding section is sewed to the section preceding it, and said stitches being connected to the adjacent 95 stitches by connecting stitches which lie between the sections adjacent the back edges thereof.
